GIRDLE

Gaylord A. Barcley, St. Petersburg, Fla.

Application May 3, 1952, Serial No. 19,578

Term of patent 14 years

(Cl. D20—2)

To all whom it may concern:

Be it known that I, Gaylord A. Barcley, a citizen of the United States of America and a resident of St. Petersburg, Florida, have invented a new, original, and ornamental Design for a Girdle, of which the following is a specification, reference being had to the accompanying drawing, forming a part thereof:

I claim:

The ornamental design for a girdle, as shown.

GAYLORD A. BARCLEY.
